UNITED STATES PATENT OFFICE.

GILBERT F. QUINN, OF BEACHMONT, MASSACHUSETTS.

TOOTHBRUSH.

Refiled for abandoned application Serial No. 717,820, filed June 4, 1924. This application filed October 26, 1927. Serial No. 228,796.

This invention relates to a tooth-brush comprising a brush back and a handle in substantial alinement with the back, and flexible brush material, projecting from one side of the back.

The object is to provide an improved arrangement of the brush material, whereby, when the brush is manipulated in the usual manner, and moved endwise forward and backward over the teeth, the brushing element forces refuse matter removed from the teeth toward longitudinal edges of the back and prevents said matter from accumulating within the brush material.

15 Of the accompanying drawings forming a part of this specification,

Figure 1 is an edge view of a tooth brush, embodying the invention.

Figure 2 is a side view of the same, looking toward the inner side.

The same reference characters indicate the same parts in all of the figures.

The brush includes an oblong brush back 12, and a handle 13, in substantial alinement 25 with the back, so that the back and handle have a common longitudinal median line, the back and handle being of any suitable rigid material and usually in one piece.

The brushing element may be of any suitable flexible brush material, such as bristles 30 14 (Figure 1), usually employed in tooth brushes and fixed to the back in any suitable manner, to project from the inner face thereof. It may be assumed that the stippling shown by Figure 2 represents the ends 35 of bristles, although I do not limit myself to bristles as the brush material.

The brush material is disposed in an inner and an outer series of substantially parallel 40 oblong rows, whose sides are substantially perpendicular to the back face from which they project. Said rows are spaced apart as shown by Figure 2, to provide refuse channels between their adjacent sides 16.

45 The rows of the outer series extend obliquely in one direction from the outer end portion to the midlength portion of the back 12. The rows of the inner series extend obliquely in a different direction from the midlength

portion to the inner end portion of the back, 50 all as shown by Figure 2. The arrangement shown and described is such that when the back is reciprocated endwise in the operation of brushing teeth, refuse dislodged by the sides 16 of said rows is delivered to the 55 channels between the rows, and passes through said channels toward the longitudinal edges of the back, one series of rows and the channels formed thereby acting to dislodge and deliver refuse at one longitudinal edge of the back, when the back is moved in one direction, and the other series of rows and channels acting similarly, when the back is moved in the opposite direction.

I prefer to space apart the outer and inner 65 series of row groups at the midlength portion of the back, to provide between the groups a transverse refuse outlet, indicated at 18 in Figures 1 and 2, said outlet communicating with the channels between the 70 rows, and extending to the longitudinal edges of the back, at the midlength portion thereof.

I claim:

1. A tooth-brush comprising an oblong 75 back, a handle longitudinally alined therewith, so that the back and handle have a common longitudinal median line, and flexible brush material projecting from the inner face of the back and disposed in an inner 80 and an outer series of substantially parallel oblong rows whose sides are substantially perpendicular to the back face from which they project, said rows being spaced apart 85 to provide refuse channels between their adjacent sides, the rows of the outer series extending obliquely in one direction from the outer end portion to the midlength portion of the back, while the rows of the inner series extend obliquely in a different direction from said midlength portion to the inner end portion of the back, the arrangement being such that when the back is reciprocated endwise, refuse dislodged by the sides of said rows, is delivered to said channels and passes therethrough toward the longitudinal edges of the back, one series of rows, and the channels formed thereby, act-

ing to dislodge and deliver such refuse at one longitudinal edge of the back, when the back is moved in one direction, and the other series acting similarly, when the back is moved in the opposite direction.

2. A tooth-brush as specified by claim 1, the outer and inner series of groups being

spaced apart at the midlength portion of the back, to provide a transverse refuse outlet communicating with the channels between the rows. 10

In testimony whereof I have affixed my signature.

GILBERT F. QUINN.
